Primary Examiner — Clare E Heflin(74) *Attorney, Agent, or Firm* — King & Spalding LLP(57) **CLAIM**

The ornamental design for an area light fixture, as shown and described.

DESCRIPTION

FIG. 1 is a bottom perspective view of an area light fixture, showing our new design;

FIG. 2 is a top perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines shown on the drawings depict portions of the light fixture that form no part of the claimed design. The dash-dot-dash lines define the bounds of the claimed design and form no part thereof.

1 Claim, 6 Drawing Sheets(56)
